UNITED STATES PATENT OFFICE.

BENJAMIN E. MEACHAM, OF LORAIN, OHIO, ASSIGNOR OF ONE-HALF TO LEOPOLD FRIEDMAN,
OF CLEVELAND, OHIO.

VALVE.

No. 866,948.

Specification of Letters Patent.

Patented Sept. 24, 1907.

Application filed November 7, 1905. Serial No. 286,256.

To all whom it may concern:

Be it known that I, BENJAMIN E. MEACHAM, a citizen of the United States, residing at Lorain, in the county of Lorain and State of Ohio, have invented new and useful Improvements in Valves, of which the following is a specification.

This invention relates to valves designed especially for controlling the supply of water and gas to a water heater, and has for its objects to produce a comparatively simple, inexpensive device of this character in which the supply of liquid and fluid will be positively and automatically controlled, one wherein, after initially setting the parts of the valve, its further adjustment is rendered unnecessary, thus obviating liability of the mechanism becoming disarranged, and one wherein the valve casing may be conveniently drained when not in use.

With these and other objects in view, the invention comprises the novel features of construction and combination of parts more fully hereinafter described.

In the accompanying drawings: Figure 1 is a longitudinal section centrally through a valve embodying the invention. Fig. 2 is a cross section taken on the line 2—2 of Fig. 1.

Referring to the drawings, I designate a valve casing having an upper water chamber 2 and a lower gas chamber 3 separated from the chamber 2 by a wall or partition 4 provided with a central opening or port 5, the casing 1, which has an inlet port 6 leading from a water main 7 to the chamber 2, being provided with a removable cover 8 having formed thereon a central tubular guide member or section 9 extended downward in the chamber 2 and closed at its lower end, said guide section, which communicates at its upper end with a service pipe or duct 10 being provided with relief openings or ports 11 and with water inlet openings or ports 12 preferably of triangular form, as shown.

Provided on the casing 1 at the outer or lower end of gas chamber 3 and for communication with the latter is an inlet port 13 leading from a gas supply main 14 and an outlet port 15 leading to a service pipe or duct 16 through which gas is supplied to the burner of a heater, not shown, and to which heater the duct 10 supplies the water to be heated, there being formed in the casing between the ports 13 and 15 a web or partition 17 having an opening or passage 18 adapted to be closed by a valve 19 threaded on the lower end of a tubular valve stem 20 movable through the opening 5 and fixed at its upper end in a rigid pressure-operated member or piston 21 movably arranged in the chamber 2 and normally closing the water inlet openings or ports 12 in the tubular guide 9 on which the piston slides.

Threaded on the stem 20 at a point between its ends

to move therewith is a second rigid pressure-operated member or piston 22 movable in the chamber 3 between the passages 5 and 18. The piston 22 is provided with an annular upstanding flange 23 to which is attached one end of a tubular coupling or sleeve 24 composed of rubber or other flexible impervious material and having its upper end attached to an annular flange 25 on the under side of the division wall 4. Arranged on the stem 20 and disposed between the wall 4 and piston 22 is a compression spring 26 that tends to hold the valve 19 closed. The stem 20 has a bore 28 that opens into the space above the piston 22 through an aperture 27 and the lower end of the bore is closed by a screw plug 29 which is removable through an opening 31 in the bottom of the valve casing 1, which opening is normally closed by a plug 30. By taking out the plugs 30 and 29, the water can be drained from the valve casing, pipe 10 and water heater supplied by the pipe, it, of course, being necessary to first cut off the supply of water from the service pipe 7.

In practice, when the water is cut off by closing the valve at the heater, the parts of the valve mechanism are in the position illustrated in Fig. 1. When the water valve of the heater is opened, the pressure of the water in the pipe 10 and in the space above the piston 21 is decreased and the water at city pressure operates on the under side of the piston 21 with a greater power than it does on the piston 22 and overcomes the latter and its spring 26 so that the pistons and valve stem move upwardly to open the gas valve 19 so that the supply of gas is automatically opened. By the upward movement of the piston 21, the ports 12 are uncovered to open the supply of water to the heater through the supply pipe 10. When the valve in the pipe 10 is closed, the pressure on both sides of the piston 21 becomes equalized through the ports 11 and the pressure of the water acting on the lower piston 22 combined with the effect of the spring 26 causes the pistons to move downwardly and close the gas supply valve 19.

Having thus fully described my invention, what I claim as new is:

In a device of the class described, a casing having a water chamber provided with a water inlet port and a gas chamber provided with inlet and outlet ports, a main partition arranged in the casing between said chambers and having an opening forming a passage of communication between said chambers; a partition arranged in the gas chamber between the inlet and outlet ports and provided with an opening forming a passage of communication between said ports, a cover applied to the casing for closing one end of the water chamber and having a tubular guide member projected into the latter, said guide member being closed at its inner end and provided between its ends with relief openings and with water inlet passages, a service pipe connected with the outer end of the tubular guide, a

rigid pressure operated piston slidably mounted on the tubular guide within the water chamber and adapted to normally close the water passages in said guide, a valve stem attached to said piston and arranged for movement through the opening in the main partition, a valve fixed on said stem and adapted to close the passage of communication between the gas inlet and outlet ports, a second rigid piston fixed on and for movement with the stem, said second piston being arranged in the gas chamber at a point between the openings in the partitions, a flexible, im-

pervious tubular coupling member engaged at its ends respectively with the main partition and second piston and a balance spring arranged on the stem between the main partition and second piston.

In testimony whereof, I affix my signature in presence of two witnesses.

BENJAMIN E. MEACHAM.
